UNITED STATES PATENT OFFICE.

ISAAC LICHTENSTEIN, OF NEW YORK, N. Y.

DESIGN FOR A HAT-BAND.

No. 38,412.

Specification for Design.

Patented Jan. 15, 1907.

Application filed November 24, 1906. Serial No. 344,986. Term of patent 7 years.

To all whom it may concern:

Be it known that I, ISAAC LICHTENSTEIN, a citizen of the United States, residing in the city, county, and State of New York, have invented a new, original, and ornamental Design for Hat-Bands, of which the following is a specification.

Reference is to be had to the accompanying drawing, forming part hereof.

The figure is a plan view of a hat-band showing my new design.

What I claim is—

The ornamental design for a hat-band, as shown.

ISAAC LICHTENSTEIN.
